K. J. E. HESSELMAN

FUEL VALVE

Filed Oct. 14, 1922

Inventor

Knut J. E. Hesselman,
By *Henry Orth Jr.* Atty.

UNITED STATES PATENT OFFICE.

KNUT JONAS ELIAS HESSELMAN, OF SALTSJO-STORANGEN, SWEDEN.

FUEL VALVE.

Application filed October 14, 1922. Serial No. 594,579.

To all whom it may concern:

Be it known that I, KNUT JONAS ELIAS HESSELMAN, a citizen of the Kingdom of Sweden, residing at Saltsjo-Storangen, Sweden, have invented new and useful Improvements in Fuel Valves, of which the following is a specification.

In the type of fuel valves which is opened due to the increased pressure during the discharge stroke of the fuel supply pump, the seat of the fuel valve is subjected to heavy stresses. This is due to the fact that the valve seat must be very narrow in order that the valve may open at a given moment. Thus the pressure on the seat will be considerable, making it necessary to build the seat of very hard material and with the very highest accuracy. In well known designs this is very difficult to obtain as the seat is situated far down in the fuel valve casing or in a member inserted therein.

This invention relates particularly to that type of fuel valves the opening of which is effected due to the said increased pressure through the intermediary of an elastic hollow member connected to the valve, as a bellows or the like. The invention is characterized, chiefly, in that the valve seat is provided at the upper edge of a separate member inserted in the valve casing, the guideway for said valve being arranged below the valve body engaging said seat.

In the accompanying drawing, a longitudinal section through a fuel valve according to this invention is shown.

With reference to the drawing, the fuel valve casing 1 is shaped as a sleeve having a fuel inlet as at 2. Inserted in the sleeve 1 at the lowermost end thereof is a plug-shaped member 3 resting with an enlarged portion on a shoulder 30 formed in the sleeve, and held in place by means of a nut 4 screwed on the lowermost threaded portion of the member 3 and engaging the lowermost end surface of the casing 1. The member 3 is formed with a central fuel passage 5. The lowermost end of said passage is enlarged and threaded internally to re-

ceive an externally threaded fuel nozzle 6. At its upper end the passage 5 is likewise 50 enlarged to form a cylindrical boring to receive and guide the stem 9 of a valve body 8 engaging a seat 7 formed at the upper edge of said enlarged portion 50 of the passage 5. The valve body 8 is formed with 55 an enlarged, disk shaped head 80 engaging a corresponding recess formed in the bottom of a bellows 10 enclosed in the casing 1 said head 80 being securely maintained in said recess by means of a nut 81, as shown. 60 The bellows 10 may be of a known design adapted to be operated by the fuel pressure to open the valve. By placing the valve seat at the uppermost edge of the member 3, the seat will be readily accessible for inspection 65 and may be readily manufactured with the highest degree of accuracy by grinding it simultaneously with the grinding of the guiding boring 50. The member 3 may, if desired, be hardened, or a hardened bushing 70 may be inserted therein. Owing to the fact that the member 3 is constructed to be inserted from the uppermost end of the valve casing, it will readily be seen, that the pressure within the casing 1 will tend to maintain 75 the member 3 against the shoulder 30, thereby rendering the tightening effective.

What I claim is:—

A fuel valve comprising a sleeve shaped casing, a tube in said casing compressible in 80 the longitudinal direction by the fuel pressure within the casing and guided at one end of the latter, a plug-shaped member inserted in the casing at the opposite end thereof, said plug member having a through-extending 85 boring and a valve seat at the inner end of said boring, an extension of said hollow tube engaging said boring to be guided therein, a valve body formed integral with said extension to engage said seat, and a 90 fuel sprayer secured to said plug member at the outer end of said boring.

In testimony whereof I have signed my name.

KNUT JONAS ELIAS HESSELMAN.
